US00D871120S

(12) **United States Design Patent** (10) Patent No.: **US D871,120 S**
(45) Date of Patent: **** Dec. 31, 2019**

(54) **PRIVACY SCREEN**

(71) Applicant: **Haworth, Inc.**, Holland, MI (US)

(72) Inventors: **Charles Schalk**, Wyoming, MI (US);
Steffen Lipsky, Holland, MI (US)

(73) Assignee: **Haworth, Inc.**, Holland, MI (US)

(**) Term: **15 Years**

(21) Appl. No.: **29/627,087**

(22) Filed: **Nov. 22, 2017**

Related U.S. Application Data

(63) Continuation of application No. 29/569,976, filed on Jul. 1, 2016, now Pat. No. Des. 803,601, which is a continuation of application No. 29/530,176, filed on Jun. 15, 2015, now Pat. No. Des. 779,237.

(57) **CLAIM**

The ornamental design for a privacy screen, as shown and described.

DESCRIPTION

FIG. 1 is a perspective view of the privacy screen embodying the new design;

FIG. 2 is a front view thereof;

FIG. 3 is a rear view thereof;

FIG. 4 is a right side view, the left side view being a mirror image thereof; and,

FIG. 5 is a top view thereof.

The portions shown in phantom lines in FIGS. 1-5 are shown for environmental purposes only and form no part of the claimed design.

1 Claim, 4 Drawing Sheets
